UNITED STATES PATENT OFFICE

2,588,850

ROLLER JEWEL SETTING TOOL

Frank Kobos, Sr., Houston, Tex.

Application December 21, 1948, Serial No. 66,434

6 Claims. (Cl. 81—7)

1

This invention relates to novel and useful improvements in tools adapted for use in conjunction with the repair or manufacture of watches or other time pieces.

An object of this invention is to retain a time piece component such as a balance pinion for setting a conventional jewel in the jewel table therein, by means of a jewel setter which includes a shank having a flattened end portion with a slot or opening therein adapted to accommodate a portion of the normal shaft associated with the balance pinion, a block movably mounted on the shank with respect thereto, the block having an opening for accommodation of another portion of the shaft and having an inner surface adapted to clampingly engage the jewel table, and also having a groove at the top portion thereof for accommodation of a jewel, the pinion being retained in the device in such a manner that the jewel may simply be slid in the groove for reception into the conventional opening in the jewel table.

Another object of this invention is to retain the time piece component in the device by a frictional bond set up between the elements of the device and the component and influenced by a spring which constantly urges the block toward the slotted end of the shank.

A further object of this invention is to prevent lateral movement of the block with respect to the slotted end of the shank by means of a guide which is associated with the block and the slotted end of the shank, the guide forming the actual seat for the said spring.

Ancillary objects and features of novel such as simplicity of structure will become apparent to those skilled in the art, in following the description of the preferred form of the invention, illustrated in the accompanying drawings, wherein:

Figure 1 is a fragmentary perspective view of the preferred form of the invention;

Figure 2 is an elevational side view of the device shown in Figure 1, and

Figure 3 is a sectional view taken substantially on the line 3—3 of Figure 2 and in the direction of the arrows.

Considerable skill is required in setting jewels in watch components. Specifically, it requires an extremely skillful person to set a jewel in the jewel table of a balance pinion in setting the roller jewel therein, in the absence of special tools or devices to assist in this operation.

Heretofore devices have been known to facilitate this operation. This invention involves improvements in devices for assisting in setting the jewel in the jewel table of such a watch component.

Various devices such as that shown in Patent No. 1,092,345 which was issued to one J. E. Ford on April 7, 1914, showed devices in this general

2

class. In the prior art it has been known to so arrive at this completed operation by the utility of pivots, pivot pins and arms associated therewith and other relatively complicated elements. A material amount of wear has been found to occur in pivotal connections in tools of this nature. Hence, it is another one of the purposes of the invention to supply an apparatus for performing the function of jewel setting which is totally devoid of pivot pins, pivotal connections and equivalent elements.

In order that a device be commercially feasible, it is essential that it be simplified, rapidly operable and reasonably inexpensive. Hence, it is another one of the purposes of the invention to accomplish those ends.

Referring now more specifically to the drawings, a handle generally indicated at 10 includes a shank 12 which has a flattened end portion 14 and a hand gripping element 16. At the end of the flattened shank there is a slot or opening 18 which extends longitudinally with respect to the shank 12.

There is a block generally indicated at 20 which is attached to the flattened end portion 14 of the shank 12 for movement with respect thereto. The block cooperating with the slotted end of the shank 12 forms a means for frictionally retaining a time piece component therebetween. For illustrative purposes, a balance pinion 22 is utilized. Hence, the balance pinion 22 includes the usual and conventional spokes 24 and hub 26. Fixed to the hub is a jewel table 28, having a jewel opening or aperture 30 therein as is conventional in the art. A shaft has one end 32 extending from one surface of the pinion 22 and the other end 34 extending from the hub 26 and also from the roller jewel table 28.

The block 20 is substantially L-shaped having a leg 38 and a shorter leg 40. The said shorter leg 40 has a pin 42 fixed thereto and extending through a suitable opening provided in the flattened end portion 14 of the shank. This pin cooperating with the pin 44 which is also attached to the shorter leg 40 of the block and which also passes through a suitable opening in the shank flattened portion 14, forms a guide to prevent lateral movement of the block 20 with respect to the shank 12. It will be noted at this point that it is within the purview of the invention to fix the pins 42 and 44 respectively to the flattened end portion 14 and have the apertures supplied in the shorter leg of the L-shaped member. This is an alternative structure contemplated in the present device.

The opening 18 is adapted to accommodate the end 32 of the shaft and the flat surface of the end portion 14 of the shank has the pinion body portion 22 seated thereon and in frictional engagement therewith. The inner surface 50 of

the said block 20 is adapted to seat on one surface of the table 28 and is adapted to frictionally engage the same. This structure and arrangement is seen best in Figure 2.

Means constantly urging the block 20 against the table 28 thereby pressing the pinion 22 against the flattened end portion 14, is provided. The preferable means consists of a conventional spring 52 which reacts on the shank and on the block. The structural arrangement is the disposition of one end of the spring against the side of the flattened end portion 14 and the other end of the spring seated on a suitable collar 56. This collar may be fixed to the pin 44.

An opening 58 is provided in the block 20 for accommodation of the shaft end 34. With this opening aligned with the slot 18, the pinion may be disposed in the device so that the jewel receiving opening 30 is directly at the end of a groove 60 which is formed in the top of the block 20. This groove has tapering sides (Fig. 3) in order that the conventionally shaped jewel may rest therein and be slid forward toward the opening 30, whence it may be easily inserted by simply moving the same forward.

In operation, the watch component is simply inserted by sliding the movable block 20 away from the flattened end portion 14 of the shank 12. Then, the inherent resiliency of the spring 52 pulls the block 20 firmly against the watch component thereby frictionally retaining it in place within the device. The jewel 62 is disposed in the groove 60 and slid forward until it is pressed into the opening 30 of the roller jewel table 28. In removal of the balance pinion or other watch component which is utilized, it is only necessary to pull the substantially L-shaped block away from the flattened end portion 14 of the shank and lift the same from its mounting.

It is apparent that variations may be made without departing from the spirit of the invention.

Having described the invention, what is claimed as new is:

1. A roller jewel setting tool comprising a handle having a slot at one end for passage of a portion of a shaft of a time piece component, a block disposed on said handle adjacent said slot and slidably laterally of said handle, a jewel receiving groove in said block disposed at substantially right angles to the plane of said handle adjacent said slot, said groove opening upwardly and toward said slot, said block having an opening which opens toward said slot for reception of another portion of the shaft of the time piece component, the inner side surface of said block being adapted to frictionally contact the jewel table of the component, and the inner surface of the handle adjacent said slot adapted to frictionally engage another portion of the component.

2. A roller jewel setting tool comprising a handle having a slot at one end for passage of a portion of a shaft of a time piece component, a block slidably disposed on said handle adjacent said slot and capable of sliding laterally of said handle, a jewel receiving groove in said block disposed at substantially right angles to the plane of said handle adjacent said slot, said groove opening upwardly and toward said slot, said block having an opening which opens toward said slot for reception of another portion of the shaft of the time piece component, the inner side surface of said block being adapted to frictionally contact the jewel table of the component, and the inner

surface of the handle adjacent said slot adapted to frictionally engage another portion of the component, and a spring reacting on said handle and said block constantly urging said block toward said handle adjacent said slot.

3. A roller jewel setting tool comprising a handle having a slot at one end for passage of a portion of a shaft of a time piece component, a block disposed on said handle adjacent said slot and slidably laterally of said handle, a jewel receiving groove in said block disposed at substantially right angles to the plane of said handle adjacent said slot, said groove opening upwardly and toward said slot, said block having an opening which opens toward said slot for reception of another portion of the shaft of the time piece component, the inner side surface of said block being adapted to frictionally contact the jewel table of the component, and the inner surface of the handle adjacent said slot adapted to frictionally engage another portion of the component, a spring reacting on said handle and said block constantly urging said block toward said handle adjacent said slot, and a guide mounted in said handle and said block to limit the travel of said block with respect to said handle.

4. For use in setting a jewel in the table of a balance pinion having a shaft projecting from opposite faces thereof, a roller jewel setter comprising a shank having a flat end portion with an opening therein for accommodation of a part of the shaft, an elongated block having a jewel table engaging surface, means mounting said block for lateral movement with respect to said shank, a groove extending toward said opening and located longitudinally in said block transverse to the length of the shank for accommodation of the jewel to be inserted in the jewel table, means reacting on said block and said shank for constantly urging said surface against the jewel table and for pressing said pinion against said shank, and said block having an aperture extending toward said opening and spaced from said groove to accommodate another portion of the shaft.

5. The combination of claim 4 and a guide operatively connected with said shank and said block preventing movement of said block with respect to said shank in a direction transverse to the longitudinal axis of said groove.

6. The combination of claim 4 and a guide operatively connected with said shank and said block preventing lateral movement of said block with respect to said shank in a direction transverse to the longitudinal axis of said groove, said block urging means including a spring, said block mounting means including pins, and said spring being disposed on one of said pins.
